UNITED STATES PATENT OFFICE.

MAX COHN, OF MILWAUKEE, WISCONSIN, ASSIGNOR OF ONE-THIRD TO
CHARLES COHN, OF SAME PLACE.

TYPE-WRITING MACHINE.

SPECIFICATION forming part of Letters Patent No. 432,982, dated July 29, 1890.

Application filed July 1, 1889. Serial No. 316,200. (No model.)

To all whom it may concern:

Be it known that I, MAX COHN, of Milwaukee, in the county of Milwaukee and in the State of Wisconsin, have invented certain new and useful Improvements in Type-Writing Machines; and I do hereby declare that the following is a full, clear, and exact description thereof.

My invention relates to type-writing machines; and it consists in certain peculiarities of construction and combination of parts, to be hereinafter described with reference to the accompanying drawings, and subsequently claimed.

In the drawings, Figure 1 represents a plan view, partly in horizontal section, and illustrates a spring-controlled frame trunnioned to standards, index-plate, type-wheel, and ribbon-winding mechanism carried by the frame, and the means for actuating the type-wheel; Fig. 2, a plan view illustrating the base of the machine, an intermittently-actuated paper-carriage arranged to travel thereon, a stop for the type-wheel, and an alarm mechanism; Fig. 3, a front elevation of the machine with parts broken away; Fig. 4, an end view of the machine partly in vertical transverse section, designed to illustrate a copy-holder secured to a standard on the base, the connection between the paper-carriage-actuating lever and type-wheel shaft, the mechanism for shifting and stopping the type-wheel, a spring-controlled shield that depends from the printing-frame, and an anvil that receives the impact of the type; Fig. 5, a vertical transverse section that more particularly illustrates certain details of construction in connection with the paper-carriage, ribbon-winding mechanism, and alarm; Fig. 6, an elevation of one end of the paper-carriage; Fig. 7, a vertical transverse section of the anvil; Fig. 8, a detail view illustrating a spring-controlled shield that constitutes part of my invention; Fig. 9, a detail view illustrating a sheave on the spring-controlled shaft of the type-wheel and a guide for the cord connecting the sheave with a bell-crank lever, and Fig. 10 a detail section of a portion of the inking mechanism.

Referring by letter to the drawings, A represents the base of my type-writer, having its

rear corners provided with standards *a*, that serve as bearings for trunnions *b* of a rectangular racking-frame *B*, having its end pieces engaged by the slotted upper ends of posts *c*, that extend from the base adjacent to the standards, and arranged on these posts to impinge against said ends of the frame are spiral springs *d*, that support said frame and automatically return the same to its normal position after a depression by the operator, pins *e* being passed through the upper ends of the posts to serve as stops for limiting the upward movement of the frame.

The sides of the frame *B* are centrally provided with bearings for a transverse shaft *C*, having a spiral spring *f* arranged thereon and fastened at one end thereto, the free end of this spring being passed under a bracket *g*, that extends inward from the adjacent side of said frame and is provided with stops for a lever *D*, that is pivoted to said side of the frame and provided with a pin *h*, for engagement with an annular groove *i* in the hub *j* of a type-wheel *E*, the latter being splined to said shaft and shifted thereon by said lever. The hub *j* of the type-wheel extends outward for a certain distance and carries a toothed wheel *F*, that comes in and out of engagement with a lug *k*, projecting from a longitudinal rail *G*, that is secured at its ends to the outer end of two parallel tracks *H* for a paper-carriage *I*, the latter being hereinafter more particularly described. The toothed wheel *F* engages the lug *k* every time the frame *B* is depressed, and this construction and arrangement of parts prevents vibration of the type-wheel *E*, whereby any selected character thereon will strike the true printing-point, perfect spacing being the result.

The type are preferably formed on strips *m*, of any suitable material, and these strips are designed to be detachably connected to the wheel *E* by any suitable means, whereby different sets of characters may be interchangeably employed in connection with the machine or worn-out type readily replaced, or a series of type-wheels may accompany the machine, one being substituted for another, as occasion requires. As shown, the type on the wheel *E* are arranged in three parallel rows and are relative to the spaces between

the teeth on the wheel F, either row of type being brought into register with the printing-point by means of the lever D, above described.

5 Detachably secured to one corner of the frame B is a segmental index-plate J, provided with a row of indentations corresponding to the type on wheel E, each of these indentations being indicated by characters that denote the corresponding characters on said wheel, and in case the type-strips or wheel be changed to present a different series of characters a corresponding index-plate would be substituted for the one now employed.

10 Pivotedly connected to the center point of the segmental index-plate is a bell-crank lever K, provided with a lug n, for engagement with the indentations on said index-plate, the inner end of this lever being connected by a cord o with a sheave L, fast on the shaft C, whereby a movement of the lever will rotate said shaft, and thus bring the desired character on the type-wheel in register with the printing-point. The spring f on the shaft C contracts in opposition to the pull of the lever K, and on the release of this lever the parts actuated thereby are returned to their 15 normal position by the expansive force of said spring.

15 In order to take up slack in the cord o, the lever K is provided with a bearing for a screw p, to which one end of said cord is secured, and arranged on this screw are set-nuts q, this construction being illustrated in Fig. 1.

20 Attached to the rear side of the frame B is a bracket r, that carries parallel rollers s, that serve as a guide for the cord o, and in order to prevent the latter from slipping off the sheave L a guard t is also connected to said side of the frame.

25 40 Depending from the front side of the frame B is a bracket M, provided with a guide u, for the spring-controlled vertical shank of a horizontal shield N, that comes under the type-wheel E, and is provided with an opening v, that registers with the printing-point, said shield being held against rotation by means of a lug w on its vertical shank, being in engagement with a slot x on said guide. (See Fig. 8.) Other brackets also depend 30 from the front side of the frame B, and these brackets are provided with bearings y, for the spindles of detachable ribbon-spools O, and bearings z, for a longitudinal shaft P, arranged at right angles to said spools and extended through one end of the frame B.

35 45 Splined on the outer end of the shaft P is a ratchet-wheel Q, provided with an annularly-grooved hub that engages with a lug a' on the adjacent end of the frame B, the latter being provided with a stud b', on which is arranged a detent c', for engagement with said ratchet-wheel. The shaft P is loose in its bearings and carries pinions d', arranged in pairs and so spaced that one pinion in each pair will engage a pinion on the spindle of the adjacent ribbon-spool, whereby the ribbon R, arranged in guides R', will be

wound from one spool to other in either direction, accordingly as said shaft is moved in or out in its bearings to bring one or the other 40 of the pinions in each pair in mesh with the pinions on the spool-spindles, intermittent rotation being imparted to the shaft by means of a spring-pawl S on the base A, arranged to actuate the ratchet-wheel Q every time the frame B is depressed, said pawl being best illustrated in Fig. 5. The type on the wheel E impact against an anvil T, having a screw-threaded stem e', that passes through a brace f' in a hollow standard U on the base A, and the anvil is vertically adjusted by means of set-nuts g', arranged on its stem to come upon opposite sides of said brace, as illustrated in Fig. 7. By adjusting the anvil T the pressure of the type is readily regulated 45 to attain good impression, especially when the machine is employed for manifold work.

50 The paper-carriage I is provided with rollers h', that travel on the tracks H, and fast to its rear side beneath this carriage is a rack i', for engagement with a pinion j' on a shaft V, that has its bearings in the adjacent end of said tracks, and on the base A, as is best illustrated in Fig. 5. The shaft V is also provided with a ratchet-wheel W, that engages a 55 spring-pawl X, pivoted to a bifurcated link Y, loose on said shaft, and pivoted in turn to a lever Z, fulcrumed on a stud k', that projects from the adjacent one of the tracks H, this lever being connected by means of a link A' with an end of the frame B, whereby each time the latter is actuated the carriage is moved a short distance in a forward direction, whereby the spacing of the printed characters is attained.

60 The base A is provided with a detachable standard B', provided at its upper end with a pulley m', and arranged to slide on this standard is a weight C', attached to the carriage I by means of a cord n', passed over the pulley m', and another pulley o' on a bracket p', attached to the base of the machine, said weight serving to take up lost motion between the rack and pinion-gear when the carriage is moved forward, as above described.

65 A spring-controlled detent D' is pivoted to a stud q' on the rear one of the tracks H, to engage the ratchet-wheel W, and a bail r' on the spring-pawl X straddles the detent, the latter and said pawl being raised out of engagement with said ratchet-wheel by means of a lever E', fulcrumed to the adjacent one of the tracks H, and provided with a lug s', that comes under said detent. When the detent and pawl are brought out of engagement with the ratchet-wheel, the carriage can be 70 adjusted on its tracks.

75 Journalized in bearings on the carriage are parallel rolls F' G', for feeding the paper, and a graduated scale H' is supported above the roll F' by means of brackets I', the latter serving also as guides to prevent the paper running crooked.

80 A shaft J' is supported in arms t' at the

front of the carriage, and splined on this shaft are guide-rolls K' for the paper.

The shaft of feed-roller F' is provided with a gear-wheel L', having a crank M', and arranged on said shaft is a notched wheel N', for engagement with a spring-detent O', as best illustrated in Fig. 6. The gear-wheel L' meshes with an idler P' on a stud u', projecting from the adjacent end of the carriage, and this idler communicates motion to another gear-wheel Q' on the shaft J'. By actuating the gear-wheel L' the line-spacing is effected.

The opposite end of the carriage is provided with a barbed finger R', that actuates a spring-controlled hammer pivoted to an arm v' of a post S' on the base A, and said post supports a bell T', designed to be struck by the recoil of the hammer when the barb on the finger passes out of contact with the pivoted foot-piece w' of said hammer. When the carriage is drawn back, the pivoted foot-piece w' of the hammer yields to the pressure of the barb on the finger R', and thus no resistance is offered to the movement.

One of the standards a on the base A is provided with a socket x' for the standard y' of a detachable spring-clip U', the latter being of ordinary construction and serving as a copy-holder.

In a former application, Serial No. 281,090, filed July 26, 1888, I have shown a trunnioned frame provided with bearings for a spring-controlled shaft that carries a type-wheel and sheave, the latter being flexibly connected to a bell-crank lever that is pivotally united to a segmental index-plate, and in the same application I show a paper-carriage provided with a rack engaged by a pinion on a shaft having stationary bearings, this shaft being provided with a ratchet-wheel that engages a spring-pawl pivoted to a bifurcated link loose on said shaft and pivoted in turn to a lever fulcrumed on a stationary stud, this lever being linked to an end of the type-wheel frame, whereby each time the latter is actuated the paper-carriage is moved a short distance in a forward direction to space the printed characters, lost motion being taken up by a weight flexibly connected to said paper-carriage. A detent is also engaged by the ratchet-wheel, and a bail or loop on the spring-pawl straddles the detent, the latter and said spring-pawl being raised out of engagement with said ratchet-wheel by a lever mechanism when it is desirable to adjust the paper-carriage on its track or to return said paper-carriage to its normal position.

Having thus described my invention, what I claim as new, and desire to secure by Letters Patent, is—

1. In a type-writer, the combination of a trunnioned frame, ribbon-spools having spindles arranged in bearings on the frame and provided with pinions, a longitudinally-adjustable shaft having its bearings in said frame and provided with pinions arranged to

come in and out of mesh with those on the spool-spindles, a ratchet-wheel splined on the shaft, and a pawl arranged in the descending path of the ratchet-wheel, substantially as set forth.

2. In a type-writer, the combination, with ribbon-spools having spindles provided with pinions, of a longitudinally-adjustable shaft carrying pinions arranged in pairs and so spaced that one pinion in each pair will engage the pinion on the adjacent spool-spindle accordingly as the shaft is adjusted in either direction, and a pawl-and-ratchet mechanism for intermittently actuating said shaft, substantially as set forth.

3. In a type-writer, the combination of a frame, a rotary adjustable shaft having its bearings on the frame, a spiral spring arranged on the shaft and fastened at one end thereto, a bracket on said frame arranged to extend over the free end of the spring, a wheel splined on said shaft and provided with type-characters arranged in parallel circles, a lever connecting said frame with the wheel, and stops for the lever, substantially as set forth.

4. In a type-writer, the combination of a frame, a rotary adjustable shaft having its bearings on the frame, a spiral spring arranged on the shaft and fastened at one end thereto, a bracket on said frame arranged to extend over the free end of the spring, a type-wheel splined on said shaft and having an annular groove in its hub, a lever having a pin engaged with said groove, and stops for the lever, substantially as set forth.

5. In a type-writer, the combination of a trunnioned frame, a rotary adjustable type-wheel carried by the frame, a bracket depending from the frame, a shield having an opening therein to register with the printing-point, and a spring-controlled shank on the shield connected to the bracket, substantially as set forth.

6. In a type-writer, the combination of a trunnioned frame, a spring-controlled rotary adjustable type-wheel having its shaft arranged in bearings on the frame, a bracket depending from said frame and provided with a slotted guide, a spring-controlled shank arranged in the guide and provided with a lug to engage the slotted portion thereof, a shield carried by the shank to come under the type-wheel, and an opening in the shield arranged to register with the printing-point, substantially as set forth.

7. In a type-writer, the combination, with an impacting mechanism, of a hollow standard internally provided with a brace, a screw passed through the brace, nuts engaging the screw on opposite sides of said brace, and an anvil carried by said screw, substantially as set forth.

8. In a type-writer, the combination of a spring-controlled shaft carrying a type-wheel and sheave, a segmental index-plate, a bell-crank lever pivoted to the index-plate, a take-up mechanism arranged on the lever, and a

cord connecting the sheave and take-up mechanism, substantially as set forth.

9. In a type-writer, the combination of a spring-controlled shaft carrying a type-wheel and sheave, a segmental index-plate, a bell-crank lever pivoted to the index-plate, a bearing on the lever, a screw arranged in the bearing, nuts arranged on the screw at opposite ends of said bearing, and a cord connecting to said screw and sheave, substantially as set forth.

10. In a type-writer, the combination of a spring-controlled shaft carrying a type-wheel and sheave, a segmental index-plate, a bell-crank lever pivoted to the index-plate, a cord connecting the lever and sheave, and a guide for the cord, substantially as set forth.

11. In a type-writer, the combination of a spring-controlled shaft carrying a type-wheel and sheave, a segmental index-plate, a bell-crank lever pivoted to the index-plate, a cord

connecting the sheave and lever, and a guard arranged to prevent the disengagement of said cord and sheave, substantially as set forth.

12. In a type-writer, the combination of a reciprocating paper-carriage, a pair of feed-rollers mounted on the carriage, a crank-actuated gear-wheel carried by one of the rollers, an idler arranged to mesh with the gear-wheel, a shaft having its bearings on said carriage, a gear-wheel carried by the shaft to mesh with the idler, and guide-rolls splined on said shaft, substantially as set forth.

In testimony that I claim the foregoing I have hereunto set my hand, at Milwaukee, in the county of Milwaukee and State of Wisconsin, in the presence of two witnesses.

MAX COHN.
